DESIGN FOR A POTATO MASHER

Henry T. Warner, Chicago, Ill.

Application February 10, 1938, Serial No. 75,036

Term of patent 7 years

To all whom it may concern:

Be it known that I, Henry T. Warner, a citizen of the United States, residing at Chicago, in the county of Cook and State of Illinois, have invented a new, original, and ornamental Design for Potato Mashers, of which the following is a specification, reference being had to the accompanying drawing, forming a part thereof.

In the drawing:

Fig. 1 is a side elevation of the potato masher, showing my new design;

Fig. 2 is a bottom plan view; and

Fig. 3 is a perspective view thereof, on a reduced scale.

I claim:

The ornamental design for a potato masher, as shown.

HENRY T. WARNER.
